FLUID LIFT

Jeddy D. Nixon, Houston, Tex., assignor of one-half to Wilson Supply Company, Houston, Tex., a corporation of Texas

Application June 1, 1937, Serial No. 145,680

1 Claim. (Cl. 103—233)

This invention relates to new and useful improvements in means for lifting fluid from wells.

This application is filed as an improvement on my copending application, filed February 1, 1937, Serial No. 123,444, patented October 4, 1938, No. 2,132,081.

One object of the invention is to provide improved means for controlling the admission of pressure fluid into a well tubing to lift the well liquid therein; whether the pressure fluid is supplied from the well or from an outside source.

Another object of the invention is to provide improved means for introducing gas or air under pressure into a well tubing at a single point below the standing liquid level therein, and so arranged that a simple and very efficient installation is had, whereby the flexibility of the device readily permits the invention to be installed at various installations to meet the different requirements necessary.

A further object of the invention is to provide an improved valve structure for controlling the admission of the pressure fluid into the well tubing, whereby standing, clogging, or faulty actuation of the valve is eliminated, and efficient operation thereof is obtained.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a diagrammatic view of a well unit constructed in accordance with the invention;

Figure 2 is a similar view showing a modified installation;

Figure 3 is a diagrammatic view showing a modified installation of a well unit;

Figure 4 is a longitudinal, sectional view of a portion of the well tubing showing the fluid inlet valve in an open and closed position;

Figure 5 is a horizontal, cross-sectional view taken on the line 5—5 of Figure 4;

Figure 6 is a similar view taken on the line 6—6 of Figure 4;

Figure 7 is a view partly in section and partly in elevation of a packer used in one of the modified installations of a well unit; and

Figure 8 is a longitudinal, sectional view of a standing valve and nipple used in another modification of the installation of a well unit.

In the drawings, the numeral 10 designates the usual well casing (Figure 1) which has a well

tubing string 12 depending axially therethrough. The upper end of the casing is screwed into the usual casing head 11, mounted above the ground level, and the upper end of the tubing is supported within the casing head in the usual manner. The above ground structure is preferably the same, as that set forth in my co-pending application before referred to, although such structure has not been shown and form no part of the present invention.

The tubing string extends substantially the full length of the casing 10, and its lower end may depend to within a short distance of the bottom of the well, or it may be spaced at some distance therefrom. The lower end of said tubing is provided with the usual screen or perforated bull plug 13. In some installations it is advantageous to hold a pressure on the oil sand and in such instances, of course, a suitable choke nipple 14 may be connected in the tubing above the bull plug near the lower end of said tubing. However, in many cases, the nipple 14 may be dispensed with.

At a point above the choke nipple 14, an elongated collar 15 forming a valve body (Figures 1, 4, 5, and 6) is connected in the tubing string 12. An internal, annular chamber 16 is formed in the valve body and has a number of inwardly directed radial guide ribs 17 extending thereinto. Also, an inwardly directed boss 18 is preferably formed integral with the collar and projects into the chamber. It is desirable, although not essential, that the ribs and boss be spaced equally around the chamber wall. The guide rib marked 17' is preferably diametrically opposite the boss 18 for a purpose which will be described later.

A radial port 19 extends through the boss and valve body and has its inner end internally screw-threaded to receive a flanged nipple 20. The port is counter-sunk at 21 to form a shoulder against which the flange of the nipple abuts. The outer end of the bore of the nipple 20 is provided with internal screw threads to receive a plug or cap 21' having an axial port 22 extending therethrough to permit fluid to enter the nipple. The inner end of the bore of the nipple is reduced to form a valve seat 22', and a ball 24 is confined within the nipple and being so arranged to engage this seat 22' to close the bore of the nipple to prevent flow therethrough.

The valve body 15 is provided externally with integral ribs or bosses 23 (Figures 1, 4, 5, and 6), so that the valve body will be spaced from the casing and the outer end of the port 22 through the cap and nipple and will not abut or contact said casing, thereby preventing the accidental or

undesirable closing or shutting off of said port. As will be seen, this would prevent the entrance of a pressure fluid from the casing into the tubing through the port 22. It is pointed out that a portion of the periphery of the ball valve 24 in the cage 20 projects into the chamber 16 of the valve body 15. When the ball is seated at the inner end of said cage (Figures 4 and 5), an elongated, cylindrical weight 25 is suspended from the lower end of a cable or wire line 26, which extends upwardly through the tubing 12 and through the casing head 11 at the surface of the well, and is movable vertically within said tubing above said bull plug. A suitable stuffing box arrangement (not shown) packs off around the upper end of said tubing.

The weight is preferably of sufficient diameter to contact the guide surfaces of all the ribs 17 and the boss 18, and it will be noticed in Figures 4 and 5 that, when the weight 25 passes through said valve body 15, said guide ribs 17, and particularly guide rib 17', will force said weight into contact with the concaved inner face of the boss 18, whereby said weight will engage the ball 24 and force the same from its seat 22' at the inner end of said cage 20. In this position, the valve 15 is opened so that liquid and pressure fluid will flow into the tubing from the casing through the port 22 of the cap 21' in the outer end of the bore of the nipple 20 through said port and until the weight 25 is removed and the ball 24 allowed to contact its seat 22'. When said weight has been lowered or raised from the valve body 15, the pressure differential of the fluids in the casing and the tubing will cause the pressure fluid to flow through the port 22 into the tubing, thereby forming a suction around the ball 24 and drawing the same onto its seat 22' at the inner end of the bore of the nipple 20, thus closing the port 19 of the valve body.

In Figure 1, a typical installation is shown in which three starting or surface controlled valves 15 are mounted in the tubing string 12. However, it is pointed out that the number of starting valves used depends on each individual installation and vary accordingly. It will be seen that the invention is very flexible and can be adjusted to suit any well condition encountered. The various elements taken into consideration include the size of the tubing being used; the size of the casing in the well; the liquid level in the well, that is, the level at which the liquid normally stands in the casing; the bottom hole pressure, that is, the pressure of the gas in the oil sand at the bottom of the well; and the amount of oil that is desired to be removed from the well each day, or at each operation.

Air, gas, or other pressure fluid is introduced into the casing 10 through one of the pipes 27 of the casing head 11 in any suitable manner desired. It is preferred that a substantially constant operating pressure be maintained in the casing and any fluctuation therein prevented, although this is not essential as the invention will as readily operate if the pressure does not vary or fluctuate to too great an extent. The wire line or cable 26 may be operated by any suitable means desired.

In operation, the fluid level of the well is ascertained and the valve bodies and other equipment to be installed are made up in the tubing string 12, in accordance with the conditions found present. The bull plug 13 or a screen of the desired length is screwed onto the lower end 75 of the tubing string 12, or onto a collar on the

lower end of the choke nipple 14, if the latter is used. The assembly is lowered into the well casing, until the bull plug or screen is at the depth at which it is desired to operate or produce from, preferably near the lower end of the casing 10 and at the upper end of the oil sand.

The weight 25, suspended from the cable 26, is inserted within the tubing and the upper end of said tubing closed as is the usual practice. The gas or pressure fluid is then introduced into the casing 10, and the weight 25 is lowered down into the uppermost starting valve 15 (Figure 1). As the gas pressure is built up in the casing 10, this pressure will be exerted upon the fluid level therein, so that the same is lowered by reason of the well fluid being forced into the tubing 12 through the ports 22 and 19, around the weight holding the valve open and up in the tubing. As this pressure continues building up, the well fluid level in the casing 10 is lowered until the well fluid level is substantially level with, or below, the port 19 of the valve 15, at which time the pressure fluid will enter said port and lift the fluid in the tubing up and out thereof. Thus, the operator at the surface of the well knows that the well fluid level is below the port 19 and then the weight may be lowered out of the uppermost starting valve. The passing of the pressure fluid through the port 19, to lift the well fluid in the tubing, 30 will form a suction around the ball valve 24, which will draw said ball valve into its seat 22' in the inner end of the bore of the nipple 20, thus closing the ports 19 and 22.

The lowering of the weight is continued until 35 the second starting valve is opened and the same operation is repeated until this valve is "kicked off", meaning the fluid in the casing being forced into the tubing and then being raised and expelled therefrom, as described above. The well 40 may be operated from this valve or any of the other valves and if desired, the third or next starting valve may be "kicked off" in the same manner. Thus, it will be seen that by operating from any of the desired valves, any amount of 45 liquid may be lifted as required to obtain the quota or proration set up for each well and it is an easy operation to change from producing oil from one valve to a higher or a lower valve in the tubing string.

The well fluid in the casing, below the port 19 of the valve being held open and the upper end of the bull plug 13, serves or acts as a packer or a closure means for the lower end of the casing, whereby it will be seen that a chamber for 55 the pressure fluid is formed thereabove and the well fluid is free to enter the tubing through the bull plug and its entrance is facilitated by the pressure fluid entering the above mentioned valve and lifting said well fluid out of the tubing.

As the fluid in the tubing is lifted, the well fluid around and below the bull plug 13 and from the oil sand is now free to enter the perforations of the bull plug and to flow upwardly through the tubing and the chamber 16 of the valve 15. It is pointed out that as the bottom hole pressure of the well is sufficient to carry the well fluid up to the standing fluid level, the well fluid will be carried up past the starting valves 15, because all of said valves are preferably mounted below the standing fluid level. The pressure fluid entering the starting valve, being held open by the weight, from the chamber formed in the casing by the well fluid in the casing below said valve, will aerate the well fluid 75

in the tubing above the valve being held open and will lift the same up and out of the tubing 12.

It is pointed that the fluid entering the tubing 5 will be lifted up by the pressure fluid, as long as one of the valves is held open. If it is desired at any time to shut down the well, that is, halt production, the weight is lifted or lowered out of the valve that was being held open. The pressure 10 fluid will close the port 19 in said valve by moving of the ball 24 onto its seat 22'.

Suitable valves (not shown) at the upper end of the well may be closed; one of said valves will be in the flow line, so as to cut off the admittance of 15 pressure fluid to the casing; and the other valve will be in the flow line of the well fluid outlet from the tubing. With the upper end of the well thus closed, the pressure in the tubing and the casing will remain the same as long as the valves (not 20 shown) at the upper end of the well and the valves 15 are closed. The assembly may be inoperative for any length of time desired, because it is not possible for the pressure to escape and, therefore, a constant, built-up pressure is maintained in the 25 casing and the tubing. However, when it is desired to again operate the well, the valves at the upper end of the well (not shown) are then opened, and the weight 25 is either lowered or raised, so as to open one of the surface controlled 30 valves 15. The bottom hole pressure will again lift the well fluid above the valve being held open, and the pressure fluid now entering said port 19 in said valve will lift the well fluid up and out of the tubing, and the well is now producing as before.

35 In Figure 1, I have illustrated the various elements of the assembly, as mounted in the tubing string 12 and spaced apart; although, it is to be understood that the various elements have to be spaced in accordance with each individual installation, and the invention is not to be limited to the number of starting valves shown, as a greater or lesser number may be used. It is pointed out that when the invention is used in different wells, 40 different conditions are present and, naturally, the invention will have to be modified to fit each individual installation. However, it is essential in all cases that the major number of starting valves 45 15, which have the ports 19 therein, and the bull plug 13 be below the standing fluid level within the well, and it is preferable to locate all of said valves 50 below said fluid level.

The usual practice of lifting well fluid by pressure has been to introduce pressure at the bottom 55 of the well, and thereby raise the entire column of fluid in the tubing the full length of the well. There is a disadvantage to lifting fluid in this manner, as an enormous pressure is required to accomplish the same, and particularly to "kick off", or start the lifting of the well fluid. As 60 illustrated by the assembly shown in Figure 1 of the drawings, the well fluid is raised relatively a small amount at a time and substantially a short distance, that is, in comparison to the length of the well tubing, and consequently, the well fluid can be raised with a much smaller pressure, which 65 results in a decreased operating cost.

In many instances, the well is operated only a limited period each day, and in such cases, it is 70 desirable that the well "kick off" or flow immediately. With all of the present flowing devices now in common use, quite some time is required to obtain production after starting the building-up of a pressure fluid in the casing, because during 75 the time the well is inactive, the well fluid in the

casing and the tubing has risen to the standing fluid level within the well. This disadvantage is overcome by the invention shown in the drawings. It is again pointed out that any suitable above-ground structure or arrangement may be used, 5 although the arrangement shown in my co-pending application is usually employed in the various installations. Although, the device has been described as utilizing gas pressure, it is obvious that air or other pressure fluid could be employed. 10

In Figure 2, I have shown another modification or setting of the invention wherein, instead of the choke nipple 14 shown in Figure 1, I have mounted a short nipple 30 having an axial passage 31 extending therethrough. The upper end of this 15 nipple 30 is provided with a ball valve 32 mounted in a cage 33 and seating on an annular replaceable seat 34. This described structure is the equivalent of what is known as a standing valve or a check valve. The operation of this form of the 20 invention is the same as has been described, and when the well fluid from the oil sand enters the bull plug 13' of Figure 2, it passes up through the axial passage 31 of the nipple 30, lifting the ball 32, and the fluid flow thereabove. Upon any 25 downward movement of said fluid or discontinuation of the upward flow, said ball 32 will drop into its seat 34, thereby closing the passage 31 through the nipple. Thus, it will be seen that the well fluid is trapped above the nipple 30 and ball valve 30 32. This fluid is lifted and raised out of the tubing 12', as has been described for Figure 1. The 35 operation of this form and the setting of the invention is the same substantially as has been described.

In Figure 3, a different form or setting of the invention is shown, which is particularly used under certain conditions encountered in oil wells of some fields. In some installations, it will be desired to use this setting of the invention. A 40 suitable packer 36 (Figures 3 and 7) is connected in the tubing string, near the lower end thereof, in place of the choke nipple 14, or the standing valve nipple 30, and this packer engages the inner wall of the casing 10' to prevent flow through the space 45 between said casing and said tubing, whereby the well fluid from the bottom of the hole is caused to flow upwardly through the tubing 12'. Although, any suitable packer may be used, I prefer to employ the packer disclosed in the drawings. 50

This packer, clearly shown in Figures 3 and 7, includes an upright, tubular mandrel 37, provided at each end with screw threads, whereby it may be readily connected in the tubing string. The upper portion of the mandrel is preferably 55 connected to the lower end of a starting valve 38', similar to the starting valve 15, connected in said tubing string (Figure 3). The lower portion of the mandrel is reduced and forms a shoulder 60 50 and carries an annular, inverted thimble 38, having its lip extending upwardly, and an elastic, cup-shaped, packing collar 39 has its lower end secured in the thimble, whereby the upper end or lip of the collar is left free to expand and contract said casing so as to pack off the space between said casing and said tubing. An annular bushing 40 is mounted on the reduced portion of the mandrel and has its upper 65 end abutting the shoulder 50. A short peripheral flange 41 is provided on the upper end of the bushing to assist in clamping the packing collar in the thimble 38 and on the mandrel 37. A coupling collar 42 is secured on the mandrel below the thimble to hold said thimble thereon. 75

and exert the necessary pressure required to clamp said packing collar 39.

A suitable bull plug 13', similar to the one described, may be connected to the collar 42, as shown, or a short length of tubing (not shown) 5 may be connected between said bull plug and said collar 42, if desired. The upper end of the mandrel 37 is connected into the lower end of the starting valve 38', so that when it is desired 10 to pull the tubing string, a suitable bar, weight, or other tripping mechanism (not shown) may be dropped down into the tubing string, thereby opening the port 19' of the valve 38'. The lower end of said bar will come to rest within the bull plug 13' and its upper end will extend 15 above said valve 38', holding this valve open until the packer is pulled from the well and then this bar may be removed from the valve 38', packer 39, and bull plug 13' at the top of the well. Thus, it will be seen that the well fluid 20 between the tubing and casing above the packer is allowed to drain back into the tubing, down

the same and through the perforated bull plug 13', in order that the weight of the well fluid above said packer will not be added to the weight of the tubing string. The operation of this form of invention is the same as has been described. 5

What I claim and desire to secure by Letters Patent is:

A well flowing assembly including, a well tubing 10 within a well bore, a series of flow valves normally closed mounted in the tubing at successive elevations below the level of column of fluid standing in said tubing, a packer mounted on the lower end of said tubing, one of said valves being positioned in close proximity to said packer, so as to serve as a bleed valve, a 15 device mounted to be lowered in said well for successively engaging the flow valves and positively opening each of said valves, and a flexible connection secured to the device for rapidly raising and lowering the same in said well. 20

JEDDY D. NIXON.
